UNITED STATES PATENT OFFICE.

IRA F. MANNY, OF MILWAUKEE, WISCONSIN, ASSIGNOR TO THE MANNY SIGNAL COMPANY
OF MILWAUKEE, WISCONSIN, A COPARTNERSHIP.

SELECTIVE SIGNALING DEVICE.

No. 902,099.

Specification of Letters Patent.

Patented Oct. 27, 1908.

Application filed December 12, 1907. Serial No. 406,178.

To all whom it may concern:

Be it known that I, IRA F. MANNY, residing in Milwaukee, in the county of Milwaukee and State of Wisconsin, have invented new and useful Improvements in Selective Signaling Devices, of which the following is a description, reference being had to the accompanying drawings, which are a part of this specification.

- 10 This invention relates to selective signaling devices for use with telephone or other systems and has for its object to provide a mechanism to be placed in the same electrical circuit at the several stations and 15 caused to be set in operation from the central or signaling station, it being within the power of the operator at the signaling station to effect the signaling at whichever station is desired without signaling the other stations.
- 20 In order to accomplish the above results the invention comprises a motor detained by a magnet controlled pawl, which when released by the first signal from the signaling station starts the mechanism in operation, 25 the subsequent signals from the signaling station serving to permit a step by step escapement of a rotary member which has yielding connection with the motor, there being a signaling member in a position with 30 relation thereto, depending upon the number of the station, where it is adapted to be engaged by the pawl when the proper number of signals has been given and when the pawl is moved out of engagement with the rotary 35 member by mechanism controlled by the operation of the motor, whereby the signaling member is detained by the pawl when the latter releases the rotary member, said rotary member being quickly moved by its 40 yielding connection with the motor to take up its lost motion caused by its detention by the pawl, there being an electrical contact on the rotary member adapted to be brought into contact with the signaling member at 45 such time to complete an electrical signaling circuit. A cam action caused by the relative movement of the rotary member with the signaling member causes the latter to move out of engagement with the pawl at or 50 after the time said signaling member makes the ringing contact for causing the signal, whereupon the signal member is restored to its normal position with relation to the rotary member by spring action and the rotary

member proceeds to complete its cycle of movement, the pawl being returned by the operation of the motor to its position for detaining the motor again at the starting position of the parts. On the signaling station sending a greater number of signals than the number of the station, the signaling at that station is avoided by the signaling member thereof having passed beyond the pawl before the pawl is released from the rotary member. However, to prevent the signaling at such station on a number of signals less than the number of the station, a guard is provided on the rotary member in the path of the pawl when the latter is released from the rotary member and in advance of the signaling member, the movement of said guard producing a movement of the signaling member out of a position of engagement with the pawl so that it is released before it effects the signaling by engaging the contact. 75

Incidental to the above construction it is a further object of this invention to provide a speed governor for the motor with an automatic clutch depending for its operation on the position of the rotary member with relation to the motor shaft, whereby the governor is coupled with and retards the operation of the motor during the detention of the rotary member by the pawl, but is disconnected therefrom to permit the motor to 80 speedily complete its cycle of operation when the rotary member is released from the pawl. 85

With the above and other objects in view the invention consists in the selective signaling device herein claimed, its parts and combinations of parts and all equivalents. 90

Referring to the accompanying drawings in which like characters of reference indicate the same parts in the several views; Figure 1 is a front elevation of a selective signaling device constructed in accordance with this invention, the local signaling circuit being shown in diagram and the parts being in their normal position; Fig. 2 is a similar view thereof with the parts in the act of producing the signaling through the local circuit; Fig. 3 is a similar view with the parts in position for releasing the signaling member from the pawl by means of the operation of the guard when a signal has been given of less number than 100 the number of the station to which this instrument belongs, the cam drum for the pawl being sectioned; Fig. 4 is a side elevation of 105

said device; Fig. 5 is a sectional elevation of the rear of the rotary member with its associated parts, showing the gearing for the speed governor and the electrical connections for the signaling contact; Fig. 6 is a vertical sectional view through these parts showing the construction of the speed governor clutch; Fig. 7 is a detail view of one of the clutch members thereof and its supporting spider; Fig. 8 is a sectional view through the rotary member on the plane of line 8—8 of Fig. 5, showing the electrical connection for the signaling contact; Fig. 9 is a detail view of the brush connection for the signaling contact; and, Fig. 10 is a sectional elevation of the cam drum and the pawl.

In these drawings, (referring to Fig. 4,) 15 represents a frame construction which desirably consists of a pair of plates connected together and held a suitable distance apart by corner posts as with ordinary clock work construction, there being a motor contained within the frame and comprising a ratchet-bearing winding shaft 16 loosely carrying a large driving gear 17, with a motor spring 18 connected at its ends to the winding shaft and the driving gear respectively, and a train of gearing 19, 20, 21, 22 and 23 increasing in speed from the driving gear 17 to a motor shaft 24 which extends a considerable distance in front of the front plate of the frame 15 and has a motor arm or starting arm 25 fixed on its end.

A disk shaped rotary member 26 is loosely mounted on the motor shaft 24 and, as shown in Figs. 5 and 6, has a yielding connection therewith which consists of a coil spring 27 housed within a recess in the rear of the rotary member and connected at its ends with the rotary member and the motor shaft 24 respectively. By reason of the yielding connection formed by the coil spring 27 between the rotary member and the motor shaft said rotary member has a tendency to turn with the motor shaft but may be detained for some time without interfering with the progress of the motor shaft.

As shown in Figs. 1 and 4, the rotary member 26 desirably takes the form of a pair of disks side by side, though being in fact a single integral structure, the front disk being of slightly less diameter than the other and each being provided with a series of escapement teeth extending part way along its periphery, the escapement teeth of the front portion being designated 28 and the escapement teeth of the back portion being designated 29. An escapement is formed with these teeth of the rotary member by means of an anchor pawl 30, which is pivotally mounted by having a ring shaped portion 31 loosely fitting upon a cam drum 32 on a shaft 33. The shaft 33 is driven to turn the cam drum and move the pawl laterally by a train of gearing 34, 35 and 36 from the motor shaft

24. One leg of the anchor pawl engages the teeth 28 of the rotary member while the other leg engages the teeth 29, and a spring 37 tends to maintain the former engagement, while an electro magnet 38, by attracting its armature 39 carried by the pawl, serves to swing the pawl against the action of the spring to release the engagement with teeth 28 and cause the engagement with teeth 29, meanwhile permitting an escapement of the rotary member which is under the spring action of the motor. The locking arm 25 fixed on the motor shaft has its outer end bent backwardly into the plane of teeth 28 and is normally engaged by the anchor pawl 30, its position with relation to the rotary member being fixed at such time at a distance in advance of the first tooth 28 by a stop pin 40 on the rotary member held in engagement with the locking arm 25 by the action of the spring 27 between the rotary member and the motor shaft. As long as the locking arm 25 is engaged by the pawl 30 all parts will remain at rest, but as soon as the magnet 38 is energized by the first signal from the signaling station, it being in the electrical circuit including the various stations, the locking arm 25 is released to set the motor in operation and continues in its movement in the direction of the arrow in Fig. 1, whether the rotary member is permitted to follow it by the escapement due to the succeeding signals or not.

While the anchor pawl 30 is loosely mounted on the cam drum 32 to be free to pivotally swing thereon and produce the escapement action for the rotary member, according to the number of signals sent, it is compelled to move laterally, after the locking arm 25 has made approximately a half revolution, by means of the cam action of said drum, the sleeve 31 of the anchor pawl being provided with a pin 41 (see Figs. 2 and 10) riding in a cam groove 42 in the periphery of said drum. This lateral motion of the pawl causes it to move out of the path of the escapement teeth 28 so as to release the rotary member after an interval of time sufficient for giving the greatest number of signals, thus permitting the rotary member to quickly turn under the action of its spring 27 to catch up with the locking arm 25. The pawl is soon returned by the return bend in the cam groove 42 into its normal position where it will engage the locking arm at the end of its single revolution and stop the mechanism in its normal position. The gearing between the drum 32 and the motor shaft is such that they operate in unison, the drum making one revolution of each revolution of the motor shaft. The pawl is kept in its proper position against the tendency of its spring 37 by means of a stop pin 43 on the frame with which it engages.

From the foregoing it will be understood

that each instrument in the signaling circuit is set in operation by the first signal from the signaling station and the rotary member thereof is advanced one tooth for each signal given, the pawl detaining the rotary member when the signals have ceased and until the motors have completed approximately a half of their cycle of operation, as determined by the position of the cams on the pawl drums, when the pawls are thrown out of engagement with the rotary members to permit them to quickly catch up to their locking arms 25 and continue therewith until the starting position is reached where the locking arms encounter the pawls which have just previously been returned to their engaging positions. In order to effect the signaling at the respective stations, the instrument of each station is provided with a signaling member 44 which comprises an arm on a ring or eccentric strap 45 which turns on an eccentric 46 carried by the rotary member. The eccentric is pivotally connected at 47 to the rotary member, but its swinging action is not involved in the ringing movement of the signaling member and for the purpose of considering this movement the eccentric may be treated as fixed on the rotary member. The signaling member 44 is positioned alongside of that tooth 28 which corresponds in number to the number of the station in which the instrument is used, being number four in the instrument shown in the drawings, and is in a position to be engaged by the pawl 30 when the latter is moved from said tooth 28 by the cam drum as before explained. The signaling member 44 is maintained in this normal position by being held against a stop pin 48 on the rotary member by means of a coil spring 49 which connects an arm 50 on the ring 45 with the rotary member. When the signaling member 44 is engaged by the pawl 30 and the rotary member is released therefrom the signaling member is detained by the pawl while the rotary member quickly turns to catch up with the locking arm 25 which has had a considerable lead owing to the length of time that the rotary member was detained by the pawl, before the latter was released therefrom. During the turning of the rotary member the eccentric 46 thereon moves in such a way as to gradually withdraw the signaling member 44 from the pawl 30, and the disengagement of the signaling member from the pawl is so timed that it does not take place until a signaling contact 51, which is mounted on and insulated from the rotary member, comes into engagement with a lug 52 on the back of the signaling member, as shown in Fig. 2, thus serving to complete an electrical circuit for causing the signaling at this station. As soon as the signaling member 44 is released from the pawl its spring 49 quickly restores it to its position against the

stop pin 48, so that the signaling at this station is only momentary.

The signaling contact 51, as shown in Fig. 8, is connected by an insulated conducting pin 53 with a contact ring 54 on the back of the rotary member and also insulated therefrom, there being a binding post 55 connected to and insulated from one of the plates of the frame 15 and carrying a brush 56 bearing upon the contact ring to maintain connection therewith throughout the movements of the rotary member. The local signaling circuit 57, as shown in Fig. 1, preferably includes a bell 58 connected with a battery 59 and having one terminal connected with the binding post 55 and the other terminal grounded on the frame 15 in any desirable manner. The signaling circuit is completed only when the signaling contact 51 is in engagement with the lug 52 on the signaling member 44, the circuit then being established through the binding post 55, brush 56, contact ring 54, conducting pin 53, insulating contact 51, the signaling member 44 engaged therewith and the frame 15 through the line 57 including the bell 58.

When the number of signals sent by the signaling station is greater than the number of any particular instrument, the signaling member of that instrument has passed beyond the pawl so that when the pawl is given its lateral movement to release the rotary member it does not engage the signaling member to produce the signaling at that station. However, when the number of signals sent from the signaling station is less than the number of any particular instrument it is necessary to have a means which will prevent the signaling member of that instrument being held by the pawl a sufficient length of time to cause it to engage the signaling contact. This means, in the form of the invention illustrated in the drawings, comprises a guard 60 carried by the eccentric 46 and normally held against a stop pin 61 on the rotary member by the action of a spring 62 which positions it alongside of the tooth 28 which immediately precedes the tooth beside which the signaling member 44 is stationed. The position of the pivotal connection 47 for the eccentric 46 is such that when the guard 60 is engaged by the pawl, which will be true in every case where the number of signals sent is less than the number of the instrument, the movement of the guard 60 away from its stop pin 61 causes the eccentric 46 to swing on its pivotal connection 47 and carry both the guard 60 and the signaling member 44 out of engagement with the pawl 30 before the signaling member engages the signaling contact 51, as shown in Fig. 3. The pawl 30 is of sufficient width to enable it to stand in the path of both the guard 60 and the signaling member 44 as soon as it releases the rotary mem-

ber. The signaling member 44 has a stop pin 63 which is engaged by the guard at such times so that the signaling member will move with the guard and the guard is of sufficient length to cause it to remain in engagement with the pawl as long as the signaling member 44 is in engagement with the pawl, thus avoiding the possibility of having the guard released first and by its return movement extend the ringing member into further engagement with the pawl so as to detain it until the signaling contact reaches it. As soon as the guard and the signaling member are drawn out of engagement with the pawl by the swinging action of the eccentric their springs 62 and 49 return them to their normal positions against their stop pins 61 and 48 respectively.

In order that the instrument should be capable of adjustment to operate as of any number within the range of the system, it is only necessary to provide for changing the location of the pivotal connection 47 of the eccentric 46 upon the rotary member and correspondingly changing the position of the stops 61 and 48 and the connections of the springs 62 and 49 with the rotary member. With this end in view the rotary member is desirably provided with a series of openings 64 arranged in an arc formation concentric with the eccentric 46 when in its normal position, thus allowing the eccentric to keep its present normal center in its various adjustments, though changing the point of pivotal connection, and also effecting the change of position of the guard and the signaling member so that they stand opposite the teeth 28 which correspond with the number of the instrument, the signaling member being along-side of the tooth of the same number as the instrument and the guard being alongside of the tooth in advance. In any such adjustment the guard and the signaling member will operate in exactly the same manner as above described for the number four instrument as shown in the drawings.

It is desirable that the speed of the motor should be accelerated after the period of signaling has passed so as to restore the instrument to its normal starting position without unnecessary loss of time, and with this object in view the motor is designed to operate at the maximum speed desired except during the signaling operation when a governor is automatically connected therewith to retard its speed, the governor being automatically disconnected as soon as the pawl is moved out of engagement with the teeth of the rotary member. The rotary member has a gear ring 65 set in an annular recess in the back thereof, said gear ring being provided with internal and external teeth at its outer edge meshing with a pinion 66 and a gear wheel 67 respectively which are mounted on a stationary supporting strip 68 conven-

iently attached to the frame. The gear wheel 67 meshes with a pinion 69 on a governor shaft 70 which carries spring mounted governor weights 71 connected to a sliding friction disk 72 which is brought more or less forcibly into engagement with a friction arm 73. The friction arm 73 is pivotally mounted and is drawn by a spring 74 against the end of an adjusting screw 75 which determines the position of the friction arm and thereby the speed at which the motor may run when under control of the governor. A pinion 76 is splined on the motor shaft 24 between the gear 36 and the rotary member 26 and is pressed upon by a coil spring 77 so as to give it a tendency to move toward the rotary member and hold cam shaped teeth 78 on its side into engagement with similar teeth 79 on a spider 80 which is secured to the rotary member. As long as the rotary member 26 is not retarded by the pawl and moves with the motor shaft 24, in other words, as long as the locking arm 25 is at or near its stop pin 40, the cam teeth 78 and 79 stand end to end as shown in Fig. 6 and the pinion 76 is held thereby out of mesh with pinion 66, but as soon as the pawl retards the rotary member, as it does during the signaling operation and until it is thrown out of engagement with the rotary member by means of its cam, the movement of the motor shaft relative to the rotary member causes the cam teeth to pass each other and the spring 77 slides the pinion 76 along the motor shaft and into mesh with pinion 66 thus connecting the motor shaft with the governor mechanism and permitting the latter to retard the operation of the motor. This condition continues until the pawl is moved laterally by its cam and the rotary member is released to catch up with the motor shaft, when the cam teeth 78 and 79 bring their cam surfaces into engagement with each other and force the pinion 76 out of mesh with the pinion 66 and thus uncouple the governor from the motor shaft, permitting the motor to speedily complete its further operation until the parts are restored to their original condition.

The operation of the invention has been described in detail incident to the description of the parts, but it may be briefly reviewed as follows: With the parts in the condition shown in Fig. 1, the first signal from central or the signaling station energizes magnet 38 and swings the pawl 30 to release the locking arm 25 and start the motor in operation, the rotary member 26 being first checked by the engagement of the first tooth 29 with one arm of the pawl, and then being detained by the engagement of the first tooth 28 with the other arm of the pawl as soon as the magnet is deenergized by the breaking of the signaling circuit. Further signal pulsations repeat the swinging move-

70

115

120

125

130

ment of the pawl, allowing the rotary member to escape step by step in its endeavor to follow the motor shaft, a tendency due to the coil spring connection 27 between them, said 5 motor shaft being steadily moved forward by the motor under restraint of the governor which is coupled therewith during the signaling. If the number of signals sent corresponds to the number of the instrument, being four in the present case, the pawl remains 10 in engagement with the tooth of the corresponding number until the motor has made a sufficient advance to cause the cam drum 32 to move the pawl out of engagement with the 15 teeth of the rotary member and into engagement with the signaling member 44 standing alongside of said tooth. As soon as the rotary member is thus released it quickly turns under the action of the coil spring 27 until it 20 catches up with the motor shaft, in the meantime bringing the signaling contact 51 into engagement with the contact lug 52 on the signaling member which is being detained by the pawl 30, as shown in Fig. 2, the 25 signaling at this station resulting from such contact being no sooner effected than the signaling member 44 is drawn out of its engagement with the pawl 30, owing to the cam action of the eccentric 46 on which it is mounted. When released the signaling member 44 resumes its position on the rotary member under the action of its spring 49 and when 30 said rotary member catches up with the motor shaft the cam teeth 78 and 79 effect the 35 disengagement of the pinion 66 to disconnect the governor from the motor and permit the motor to speedily return the parts to their normal position where they are stopped by the reengagement of the locking arm 25 with 40 the pawl 30.

Should the number of signals sent be greater than the number of the instrument, the signaling member would have passed beyond the pawl 30 so that when the pawl is 45 thrown out of engagement with the rotary member the signaling member moves along with the rotary member without being engaged by the pawl and consequently the signaling at this station is not produced. When, 50 however, the number of signals sent is less than the number of the instrument the guard 60 is first engaged by the pawl when the pawl releases the rotary member and by swinging the eccentric on its pivotal connection 47 both the guard and the signaling member are released from the pawl before the 55 signaling contact 51 reaches the signaling member, as shown in Fig. 3, and consequently the signaling at this station is not 60 produced.

By means of this invention a number of telephone or other instruments may be connected in the same circuit and the signaling may be produced at any one desired without 65 signaling any of the others, and thus multi-

ple party lines may be established with the resulting saving in cost of service and without the annoyance to the subscribers of having to hear the signals intended for other parties.

70

What I claim as my invention is;

1. A selective signaling device, comprising a suitably operated pawl, a motor driven rotary member having escapement teeth engaged by the pawl, means for moving the pawl out of the path of the escapement teeth, and a signaling member in position to be engaged by the pawl when the pawl is moved out of the path of the escapement teeth from the tooth corresponding to the number of the signaling device for causing a signaling.

75

2. A selective signaling device, comprising a suitably operated pawl, a motor driven rotary member having escapement teeth engaged by the pawl, means for moving the pawl out of the path of the escapement teeth, a signaling member movable with the rotary member in position to be engaged by the pawl when the pawl is moved out of the path of the escapement teeth from the tooth corresponding to the number of the signaling device, and a signaling circuit with a contact carried by the rotary member and adapted to be closed when the said contact engages the signaling member by reason of the detention of the signaling member by the pawl.

80

3. A selective signaling device, comprising a suitably operated pawl, a motor driven rotary member having escapement teeth engaged by the pawl, means for moving the pawl out of the path of the escapement teeth, a signaling member moving with the rotary member in position to be engaged by the pawl when the pawl is moved out of the path of the escapement teeth from the tooth corresponding to the number of the signaling device, a signaling contact carried by the rotary member and insulated therefrom and adapted to move into engagement with the signaling member when the latter is detained by the pawl, and means for moving the signaling member out of engagement with the pawl when the engagement of the signaling contact has been made therewith.

85

4. A selective signaling device, comprising a suitably operated pawl, a motor driven rotary member having escapement teeth engaged by the pawl, means for moving the pawl out of the path of the escapement teeth, a signaling member movably mounted on the rotary member eccentric thereof in position to be engaged by the pawl when the pawl is moved out of the path of the escapement teeth from the tooth corresponding to the number of the signaling device, and a signaling contact carried by the rotary member and insulated therefrom and adapted to be moved into engagement with the signaling member when the latter is detained by the pawl, the movement of the rotary member

with relation to the signaling member serving to move the latter out of engagement with the pawl.

5. A selective signaling device, comprising a suitably operated pawl, a motor driven rotary member having escapement teeth engaged by the pawl, means for moving the pawl out of the path of the escapement teeth, an eccentric mounted on the rotary member, 10 a spring actuated signaling member mounted to turn on the eccentric and normally standing in position to be engaged by the pawl when the pawl is moved out of the path of the escapement teeth from the tooth corresponding 15 to the number of the signaling device, and a signaling contact carried by the rotary member and adapted to move into engagement with the signaling member to complete a signaling circuit when the signaling member is detained by the pawl, the movement of the rotary member with relation to the signaling member serving to cause the eccentric to move the signaling member out of engagement with the pawl 20 when the signaling contact is made.

6. A selective signaling device, comprising a suitably operated pawl, a motor driven rotary member having escapement teeth engaged by the pawl, means for moving the pawl out of the path of the escapement teeth, a signaling member movable with the rotary member and located in position to be engaged by the pawl for causing a signaling when the pawl is moved out of the path of the escapement teeth from the escapement tooth corresponding to the number of the signaling device, and a guard beside the preceding escapement tooth in position to be engaged by the pawl for preventing the signaling. 30

- 40 7. A selective signaling device, comprising a suitably operated pawl, a motor driven rotary member having escapement teeth engaged by the pawl, means for moving the pawl out of the path of the escapement teeth, a signaling member movable with the rotary member and positioned beside the escapement tooth which corresponds in number to the number of the signaling device and in position to be engaged by the pawl when the pawl is moved out of the path of the escapement teeth, a signaling contact on the rotary member to move into engagement with the signaling member when the latter is detained by the pawl, means for disengaging the signaling member from the pawl when the signaling contact has made its engagement therewith, and a guard movable with the rotary member and located beside the escapement tooth preceding the one corresponding to the number of the signaling instrument and in position to be engaged by the pawl when the pawl is moved out of the path of the escapement teeth and adapted when so engaged to move the signaling member out of position for engagement with the pawl be-

fore the signaling contact moves into engagement with the signaling member.

8. A selective signaling device, comprising a suitably operated pawl, a motor driven rotary member having escapement teeth engaged by the pawl, means for moving the pawl out of the path of the escapement teeth, an eccentric mounted on the rotary member, a signaling member movable with the rotary member and mounted on the eccentric in position beside the escapement tooth which corresponds to the number of the signaling device to be engaged by the pawl when the pawl is moved out of the path of the escapement teeth, a signaling contact on the rotary member to move into engagement with the signaling member when the latter is detained by the pawl, said eccentric serving to cause the signaling member to move out of engagement with the pawl when the signaling contact moves into engagement with the signaling member, and a guard located beside the escapement tooth preceding the one corresponding to the number of the signaling device and in position to be engaged by the pawl when the pawl is moved out of the path of the escapement teeth and when so engaged being adapted to move the eccentric to move the signaling member out of position for engagement with the pawl before the signaling contact engages with the signaling member. 70

9. A selective signaling device comprising a suitably operated pawl, a motor driven rotary member having escapement teeth engaged by the pawl, means for moving the pawl out of the path of the escapement teeth, an eccentric pivotally mounted on the rotary member, a signaling member movable with the rotary member and mounted on the eccentric in position beside the escapement tooth which corresponds to the number of the signaling device to be engaged by the pawl when the pawl is moved out of the path of the escapement teeth, a signaling contact on the rotary member to move into engagement with the signaling member when the latter is detained by the pawl, said eccentric serving to cause the signaling member to move out of escapement with the pawl when the signaling contact moves into engagement with the signaling member, and a guard mounted on the eccentric and normally standing in position beside the escapement tooth in advance of the one corresponding to the number of the signaling device to be engaged by the pawl when the pawl is moved out of the path of the escapement teeth for causing the eccentric to swing on its pivotal connection and move the signaling member out of position for engagement with the pawl before the signaling contact engages with the signaling member. 100

10. A selective signaling device, comprising a suitably operated pawl, a suitably driven motor shaft, a rotary member loosely 110

mounted on the motor shaft, a spring connecting the rotary member with the motor shaft, escapement teeth on the rotary member engaged by the pawl, means for moving the pawl out of the path of the escapement teeth, an arm on the motor shaft normally engaged by the pawl, a signaling member movable with the rotary member and located beside the escapement tooth corresponding to the number of the signaling device in position to be engaged by the pawl when the pawl is moved out of the path of the escapement teeth, and a signaling contact on the rotary member to engage the signaling member when the latter is held by the pawl.

11. A selective signaling device, comprising a suitably operated pawl, a suitably driven motor shaft, a rotary member loosely mounted on the motor shaft, a spring connecting the rotary member with the motor shaft, escapement teeth on the rotary member engaged by the pawl, means for moving the pawl out of the path of the escapement teeth, an arm on the motor shaft normally engaged by the pawl, an eccentric pivotally mounted on the rotary member, a spring actuated signaling member on the eccentric normally held beside the escapement tooth corresponding to the number of the signaling device and in position to be engaged by the pawl when the pawl is moved out of the path of the escapement teeth, a signaling contact on the rotary member adapted to move into engagement with the signaling member when the signaling member is detained by the pawl, the position of the eccentric being such as to cause the signaling member to disengage the pawl after the signaling contact has engaged the signaling member, and a spring actuated guard connected with the eccentric and located beside the escapement tooth in advance of the one corresponding to the number of the signaling device and in position to be engaged by the pawl when the pawl is moved out of the path of the escapement teeth, the engagement of the pawl with the guard serving to swing the eccentric on its pivotal connection and move the signaling member out of position for engagement with the pawl before the signaling contact moves into engagement with the signaling member.

12. A selective signaling device, comprising an escapement pawl, an electro magnet for operating the pawl, a motor driven rotary member having escapement teeth engaged by the escapement pawl, a motor driven drum on which the escapement pawl is mounted, a pin on the escapement pawl riding in a cam groove of the drum whereby the pawl is caused to move laterally out of the path of the escapement teeth, a signaling member carried by the rotary member for engagement with the pawl when the pawl is moved out of the path of the escapement

teeth, and means for causing a signaling as the result of such engagement of the signaling member by the pawl.

13. A selective signaling device, comprising an escapement pawl, an electro magnet for operating the pawl, a motor, a rotary member driven thereby having escapement teeth engaged by the escapement pawl, a drum driven by the motor on which the escapement pawl is mounted, a pin on the escapement pawl riding in a cam groove of the drum whereby the pawl is caused to move laterally out of the path of the escapement teeth, a signaling member carried by the rotary member for engagement with the pawl when the pawl is moved out of the path of the escapement teeth, and a signaling contact carried by the rotary member and adapted to engage the signaling member when the latter is detained by the escapement pawl for causing a signaling.

14. A selective signaling device, comprising a suitably mounted pawl, an electro magnet for operating the pawl, a suitably driven motor shaft, a rotary member loosely mounted on the motor shaft and provided with escapement teeth adapted to be engaged by the pawl, a spring yieldingly connecting the rotary member with the motor shaft, an arm on the motor shaft engaged by the pawl and adapted to start the motor in operation when released by the pawl, means for moving the pawl out of the path of the escapement teeth, a signaling member movable with the rotary member in position to be engaged by the pawl when it is moved out of the path of the escapement teeth from the escapement tooth corresponding to the number of the signaling device, a signaling means caused to be operated by the engagement of the pawl with the signaling member, a speed governor for the motor shaft, and means for connecting and disconnecting the speed governor with the motor shaft dependent in its operation upon the relation of the rotary member to the motor shaft.

15. A selective signaling device, comprising a suitably mounted pawl, an electro magnet for operating the pawl, a suitably driven motor shaft, a rotary member loosely mounted on the motor shaft and provided with escapement teeth adapted to be engaged by the pawl, a spring yieldingly connecting the rotary member with the motor shaft, an arm on the motor shaft engaged by the pawl and adapted to start the motor in operation when released by the pawl, means for moving the pawl out of the path of the escapement teeth, a signaling member carried by the rotary member in position to be engaged by the pawl when it is moved out of the path of the escapement teeth from the escapement tooth corresponding to the number of the signaling device, a signaling contact on the rotary member adapted to move

into engagement with the signaling member when the signaling member is detained by the pawl, a signaling circuit established by the engagement of the signaling contact with the signaling member, a speed governor for the motor shaft, a spring pressed pinion splined on the motor shaft, a cam means between the pinion and the rotary member for causing the pinion to move laterally according to the relation of the rotary member to the motor shaft, and a train of gearing connected with the speed governor and in position to be engaged by the pinion in one of its positions.

16. A selective signaling device, comprising a motor, a motor shaft driven thereby a rotary member loosely mounted on the motor shaft, a spring yieldingly connecting the rotary member with the motor shaft, escapement teeth on the rotary member, a cam drum geared to the motor shaft, an anchor pawl pivotally mounted on the cam drum and adapted to engage the escapement teeth of the rotary member, said cam drum being adapted to move the anchor pawl laterally out of the path of the escapement teeth, an electro magnet for operating the pawl, an arm on the motor shaft normally engaged by the pawl, an eccentric pivotally mounted on the rotary member, a spring actuated signaling member mounted on the eccentric and located beside the escapement tooth corresponding to the number of the signaling device and in position to be engaged by the pawl when the pawl is moved out of the path of the escapement teeth, a signaling contact

on the rotary member adapted to engage the signaling member when the signaling member is detained by the pawl, a signaling circuit established by the engagement of the signaling contact with the signaling member, the movement of the rotary member with relation to the signaling member causing the eccentric to release the signaling member from the pawl after the signaling circuit has been completed, a spring actuated guard connected with the eccentric and located beside the escapement tooth in advance of the one corresponding to the number of the signaling device and in position to be engaged by the pawl when the pawl is moved out of the path of the escapement teeth, the engagement of the guard with the pawl serving to swing the eccentric and remove the signaling member from the position of engagement with the pawl before the signaling contact engages the signaling member, a spring pressed pinion splined on the motor shaft, a cam engagement between the rotary member and the pinion for causing the pinion to move laterally on the motor shaft according to the relation of the rotary member with the motor shaft, and a speed governor for the motor shaft having a train of gearing in position to mesh with the pinion in one of its positions.

In testimony whereof, I affix my signature, in presence of two witnesses.

IRA F. MANNY.
